BRASSIÈRE HAVING ELASTIC CUPS

Theo B. Schaumer, Los Angeles, Calif.

Application May 16, 1949, Serial No. 93,522

1 Claim. (Cl. 2—42)

1

This invention relates to brassières, and more particularly to brassières that are provided with cups made from elastic material.

In order to mold and support the breasts of an individual, it is common to provide rows of stitching on the cups. In this way, it is possible to maintain a desirable contour.

It is one of the objects of this invention to provide a brassière structure that properly confines and shapes the breasts without the necessity of custom fitting. The invention is especially useful for aiding the figure where the breasts have a relatively small diameter, but require support.

In order to accomplish this result, the cups are made so that the depth of the cup can accommodate itself to the breast, and the taper from the base to the apex is resiliently adjustable to the figure. The cups are thus made from elastic material that is resilient at least in the direction transverse to the axis of the cup. Stitching on the cups is provided to permit stretching annularly around the cup, said stitching serving to reinforce the cup in the direction from the base to the apex. When the cup is lined, the lining is made sufficiently yielding to accommodate itself readily to the conformation of the breasts.

It is another object of this invention to provide a brassière of generally improved construction.

This invention possesses many other advantages, and has other objects which may be made more clearly apparent from a consideration of several forms in which it may be embodied. Such forms are shown in the drawings accompanying and forming part of the present specification. These forms will now be described in detail, illustrating the general principles of the invention; but it is to be understood that such detailed description is not to be taken in a limiting sense, since the scope of the invention is best defined by the appended claim.

Referring to the drawings:

Figure 1 is a pictorial view of a brassière shown as in use on a person;

Fig. 2 is an enlarged fragmentary front view of the brassière shown in Fig. 1;

Fig. 3 is a fragmentary view, similar to Fig. 2, of a modified form of the invention;

Fig. 4 is a diagrammatic view of one of the cup sections.

The brassière includes two cups 1 and 2 joined to a body-encircling portion. This body-encircling portion includes a central member 3 and the sides 4 and 5. The sides 4 and 5 taper to their ends and are provided with detachable fast-

eners, such as the hooks 6 on side 4 and corresponding eyes (not shown) on side 5. These sides 4 and 5 are made from one-way stretch fabric, the stretch being permitted in a horizontal direction.

Each of the cups is similarly formed, and the description of one of them is sufficient to serve as a description for both.

Thus, cup 1 is made of four sections 7, 8, 9 and 10, joined together by seams 11 formed by lines of inelastic threads. Each of the cup sections 7, 8, 9 and 10 is formed of elastic fabric. As illustrated most clearly in Fig. 4, the elastic fabric has a one-way stretch in a direction indicated by the arrow 12, that is transverse to the direction of the seams 11. The bases of the cups are sewed to the sides 4 and 5 and to the central section 3. Elastic webbing 13, 14 and 15 can be sewn on the inner side edges of the brassière by the aid of zig-zag seams, such as 16, to permit the body-encircling portion of the brassière to stretch in a horizontal direction. Conventional adjustable shoulder straps 17 are also provided.

Each of the cup sections 7, 8, 9 and 10 may be provided with a plurality of inelastic lines of stitching 18 that extend in a direction from the base of the cup toward the top or apex. These supplemental lines of stitching prevent elongation of the cups 1 and 2. However, they do not prevent expansion of the cups in a lateral direction to increase the diameter. Accordingly, a breast that is normally deep may be more effectively confined to produce the desired contour. The cups of the brassière thus accommodate the enlargement of the base of the breast, due to confinement of the breast by the lines of stitching 18.

Preferably, the central portion 3 which separates the two cups 1 and 2 may be made of one-way stretch material in which stretch is permitted in a vertical direction. Furthermore, a short piece of elastic webbing 19 can extend below the arch of the center member 3 to assist in urging the cups against the body of the wearer.

The inelastic seams 11 and the inelastic lines of stitching 18 thus limit outward protrusion of the breasts, while the cups can comfortably confine and shape the breast due to the stretching in the direction illustrated by the arrows 20 in Fig. 2.

The elastic webbing 19 may be omitted if desired, and Fig. 3 shows such a form. Furthermore, the brassière cups may be lined or left unlined, as desired; and the cup material may be

made of two-way stretch fabric in order to lend greater flexibility to it.

The inventor claims:

In a brassière: a pair of breast cups; a pair of side members made from fabric that is elastic in a direction around the body of the wearer and inelastic transversely of said direction; each side member being joined to the base of a respective cup; and a central portion extending between the cups and joining the side members; each of said cups being made from a plurality of fabric sectors; each sector having a substantially triangular shape, the apices of the sectors converging to form the apex of the cup; the bases of the sectors together defining the base of the cup; 15 each of the sectors being elastic only in a direction substantially parallel to the base of each sector; the sides of the sectors being joined together by seams that prevent stretching in a direction from the base to the apex of each sector; 20

and each sector having at least one additional line of inelastic stitching extending from the base to the apex of the sector.

THEO B. SCHAUER.
